FRANK SCELZ, OF HARRISON, NEW YORK.

WINDOW-VENTILATOR.

1,353,789.

Specification of Letters Patent. Patented Sept. 21, 1920.

Application filed February 9, 1920. Serial No. 357,464.

To all whom it may concern:

Be it known that I, FRANK SCELZ, a subject of the King of Italy, and a resident of Harrison, in the county of Westchester and State of New York, have invented a new and Improved Window-Ventilator, of which the following is a full, clear, and exact description.

It is well understood that any number of devices have been constructed with a view of providing a window ventilator which is especially adaptable for a sleeping room, to be used at night.

These devices have for the most part proven impractical for the reason that no adjustment of the ventilator has been provided, so that where it has been merely desirable to provide a smaller opening, so as to permit of adequate ventilation without the room becoming too completely chilled, this has been impossible.

A further defect in devices heretofore known has existed in that the air was not properly filtered, or cleaned, which is particularly to be desired in winter when great numbers of heating plants are in operation.

In devices which have provided a certain amount of filtering action on the air, no provision has been made for the cleaning of the filtering element so that the ventilator quickly became unsightly.

A further defect in devices of this nature was to be found in that the same were interposed between the sash and frame, so that upon the ventilator being once positioned, it was impossible to move the frame.

I have now invented an improved type of ventilator which will permit a free movement on the part of the frame, subsequent to the ventilator having been properly positioned, which ventilator will further incorporate a filtering element structure insuring against the entry of impure air into the room, the filtering element being readily cleanable and at all times sightly; the window ventilator also incorporating structure which will permit of an adjustment of the flow of air through the same.

Further objects of my invention will appear in the annexed specification and drawings which represent one practical embodiment of the same, and in which—

Figure 1 is a sectional view of a window sash and frame, having associated therewith my improved type of ventilator.

Fig. 2 is a rear view thereof showing the

ventilator in a position permitting the entry of only a small amount of air which will be properly filtered.

Fig. 3 is a reduced rear view of the entire ventilator showing the parts of the same in a position permitting the influx of a greater amount of air than is permitted by the arrangement of the parts illustrated in Fig. 2.

In all of these views like reference numerals designate similar parts, and the reference numeral 1 indicates a window frame, conventional in all respects, and slidably in the sash 2. My improved type of window ventilator is shown in applied position with respect to these parts, and is held in this position by any suitable means such as pins 3, projecting into depressions 4 in the upper face of the sash, the ventilator being removably held in this position by any suitably retractable pins 5, which are adapted to project into sockets forming a part of the side members of the sash 2.

Referring now specifically to the construction of my window ventilator, it will be seen that the same includes a frame 6 of preferably rectangular construction, although the same may take any desired shape, which frame includes a cut-out portion 7.

Associated with the frame 6, and arranged adjacent the edges of the cut-out portion 7 are a pair of elliptically arranged under-cut strips 8. Extending between the ends of these strips are a further pair of strips 9, between which lies a further strip 10 interposed between the strips 8 and extending parallel to one of the same, that face of the strip 10 nearest to the strip 8, which it parallels, being under-cut as has been indicated at 11, the side strips 9 being also notched adjacent this under-cut portion so as to complete communication with such under-cut portions adjacent the end of the strip for a purpose more fully hereinafter specified.

A screen 12 is suitably applied to the ventilator and is adapted to be permanently associated therewith in this position. Now with a view of providing a filtering element, a piece of any suitable material 13 is cut so as to have its longitudinal edges bowed away from one another, thus conforming in outline to the elliptically disposed strips 8 and side strips 9. Adjacent the edges of the piece of material 13, and associated with the same by any convenient means, is a resiliently or otherwise contractible band 14.

It will now be seen that upon the ventilator having been applied to the sash in the manner illustrated in Figs. 1 and 2, that it will be possible to move the frame 1 by virtue of the fact that the ventilator lies in a plane in front of the plane through which the frame 1 travels, and it will thus be possible to regulate the amount of air entering such ventilator by lowering or raising the frame 1. Insects will be prevented from entering through the ventilator by means of the screen 12, and the material 13 will exclude any possibility of dirt entering through the ventilator.

It will be appreciated that the material 13 is held in applied position by virtue of the contractible band 14 which lies in the under-cut portions of the strips 8 and 9. If it is now desired to permit a greater amount of air to enter into the ventilator a similar strip 13 may be utilized, in which event the band 14 of the strip 13 will seat in the under-cut portion 11 of the strip 10, this being permitted by means of the notched parts of the strips 9.

It will be appreciated that the material 13 aside from serving as a filtering element also acts as a protector for the parts of the ventilator, and particularly the screen 12 in the event of rain, and it will also be appreciated that by virtue of the fact that the longitudinal edges of the material 13 are always held by the elliptically disposed strips that the material will always be firmly and neatly stretched upon the ventilator, at the same time by virtue of its application, being readily detachable for the purpose of cleaning.

Obviously numerous modifications of structure might be resorted to without departing from the scope of my claims which read:

I claim;

1. A window ventilator, including a frame

formed with a cut-out portion, strips attached to said frame and adjacent said cut-out portion, certain of said strips being elliptically arranged with respect one to the other, and a piece of material adapted to be associated therewith and adapted to be held in stretched condition thereby.

2. A window ventilator, including a frame formed with a cut-out portion, strips attached to said frame and adjacent said cut-out portion, certain of said strips being elliptically arranged with respect one to the other, and a piece of material adapted to be removably associated therewith and adapted to be held in stretched condition thereby.

3. A window ventilator, including a frame formed with a cut-out portion, undercut strips attached to said frame and arranged attached to said frame and arranged adjacent the edges of said cut-out portion, a strip of material conforming to said cut-out portion, and a contractible band associated with said strip of material, and adjacent the edges thereof, and adapted to seat against the under-cut portion of said strips.

4. A window ventilator, including a frame formed with a cut-out portion, under-cut strips attached to said frame and arranged adjacent the edges of said cut-out portion, the strips arranged adjacent the longitudinal edges of the cut-out portion being elliptically disposed one with respect to the other, and additional strips extending across the face of said cut-out portion and parallel to one of the strips extending adjacent one of the longitudinal edges of said cut-out portion, said latter strip being under-cut along the side nearest to the strip which it parallels, and a piece of material formed with a contractible band adapted to be removably applied to certain of said strips said material being held taut by means of said elliptically disposed strips.

FRANK SCELTZ.
